SECONDARY MULTIPLICATION POWER TUBE

Arthur A. Varela, Washington, D. C.

Application October 13, 1941, Serial No. 414,771

9 Claims. (Cl. 250—27)

(Granted under the act of March 3, 1883, as amended April 30, 1928; 370 O. G. 757)

1

In intermittent service at high power levels where operation occurs for very short intervals and during a small percentage of the time, a thermionic emitter in ultra high frequency power tubes presents a severe limitation by reason of its necessary large size and high heat dissipation. It also greatly reduces the overall efficiency because continuous heating of the emitter is necessary.

It is a purpose of this invention to provide electronic power amplifiers and oscillation generators for ultra high frequency operation at very high power levels wherein the electronic current is obtained by bombardment and secondary multiplication. In this manner the electron source is operative only during operating periods of the tube so that full advantage is taken of intermittent operation. The tubes are furthermore not subject to the frequency limitations present in valvular grid tubes and should show good efficiency at very high frequencies.

Other purposes and objects will become apparent from consideration of the following description when taken with the accompanying drawings in which:

Fig. 1 is a graph showing the relationship between secondary emission and primary voltage;

Fig. 2 is a diagrammatic representation of a tube embodying the invention together with its accompanying circuits;

Fig. 3 is a graph showing the relation of electron travel to characteristics existing within the tube;

Fig. 4 is a diagrammatic representation of a second form of tube embodying the invention together with its accompanying circuits;

Fig. 5 is a graph similar to that of Fig. 3 but having reference to the tube of Fig. 4;

Fig. 6 is a diagrammatic representation of a tube constituting a third embodiment of the invention together with the accompanying circuits;

Fig. 7 is a view of a fragment of a tube shown in Fig. 6;

Fig. 8 is a diagrammatic representation of a tube constituting a fourth embodiment of the invention together with its accompanying circuits;

Figs. 9, 10 and 11 are sectional views of various forms of electrodes which are preferred for use in the tubes illustrated in the preceding figures, and

Fig. 12 is a diagrammatic representation of a portion of the serrated emitting surface of the electrode shown in Fig. 11.

When certain materials are bombarded by electrons the release of secondary electrons from the

2

material results. The number of secondary electrons thus released depends upon the velocity of the bombarding electrons and has a general function as shown in Fig. 1 wherein the ordinate σ is the ratio of the secondaries released to the primaries arriving and the abscissa is the voltage of arrival of the primary electrons. It will be necessary that the ratio increases linearly with the primary voltage up to about 400 volts after which the rate of increase decreases until the ratio becomes substantially constant. The maximum ratio may be as high as 10. In the tubes constructed according to the invention and described hereinafter this phenomenon is employed to obtain modulated electron currents of high density by shuttling the electrons back and forth between two electrodes having high secondary emissivity in such manner that multiplication is obtained during each collision cycle.

In the tubes shown in Fig. 2 reference character 1 indicates a disk electrode having its surface treated for high secondary emission. Reference characters 2 and 3 indicate cylindrical electrodes coaxially located with respect to each other and the emitting surface of electrode 1. At the opposite end of the tube from electrode 1 is located a second emitter electrode 4 preferably having the shape of a truncated cone. Located behind the electrode 4 is an electrode 5 preferably having the shape of a disk as shown and of such size as to exceed the lateral dimensions of 4. An evacuated glass envelope 6 encloses the electrodes. The cylinders 2 and 3 may either be outside the envelope as shown or may be enclosed in it. Solenoids 7 and 7' provide a magnetic field which is coaxial with the tube. Electrode 1 is at R. F. ground; cylinder 2 is connected to an R. F. tuned circuit 8; cylinder 3 and electrode 4 are at R. F. ground and electrode 5 is connected to an R. F. tuned circuit 9 which is regeneratively coupled to the circuit 8. D. C. potentials are applied by source 10 such that cylinders 2 and 3 are rendered positive relative to electrode 1 and electrodes 4 and 5 are further positive. The solenoids 7 and 7' are disposed so that the magnetic field bends out in the neighborhood of 4. The operation of this tube is as follows:

It will be seen that an R. F. field exists between electrode 1 and the end of cylinder 2 and between cylinder 3 and the other end of 2. Potentials and spacing are made such that the electron transit time from a to b is approximately 90° and the sum of the transit times from b to c and that of the secondary electrons from c to b is approximately 180°. Electrons leaving the electrode 1

when the R. F. field is zero and becoming negative will arrive at b when the field here is maximum with a positive accelerating polarity. These electrons will then arrive at electrode 4 with a net velocity equal to the peak R. F. voltage of cylinder 2. These electrons will then release a number of secondary electrons from electrode 4 which will travel back down the tube toward 1. They will arrive in field b 180° after the passage of the primary electrons and hence this field will again be maximum and with a positive accelerating polarity. The field at a will be passing through zero upon the arrival of the electrons at 1 while at the same time the R. F. voltage at 2 will be at its peak. New secondaries will be released from 1 and these will repeat the cycle. Since this multiplication process is sustained current densities may rapidly build up to very high values. The multiplication cycle as just described is indicated graphically at Fig. 3. It will be necessary that the electrons considered bear the optimum phase relation for sustained multiplication. It is apparent that electrons bearing any other phase relation will produce lower or zero multiplication in accordance with the curve of Fig. 1. Hence the electric current will not be continuous in operation but will be in the form of discrete clouds. These electron clouds are kept focused along the axis of the tube by the action of the magnetic field. However, this focusing action is opposed by the mutual repulsion of the electrons and can maintain only a limited electron density depending upon its strength. The electric field of 5 will penetrate around the edges of 4 and will attract electrons coming into it. This combined with the curvature of the magnetic field in the vicinity of 4 will cause secondaries from the outer portion of 4 to go to 5. Secondary electrons leaving 4 will be much more susceptible to the field of 5 than will the oncoming primaries because the secondaries leave with virtually zero velocity and are readily deflected whereas the primaries approach with relatively very high velocity and are not so readily deflected. Hence a considerably greater current may arrive at 4 than will pass down the tube from it. The excess electrons which equal σ , times the current arriving, minus the current returning down the tube, then flow to the anode 5. Because of the high D. C. potential of 5 the electron current may be made to pass to it when its radio frequency voltage is negative and hence may generate R. F. power. The power input to 8 may be taken as equal to the R. F. voltage of cylinder 2 times the current it accelerates. Likewise the power output of 5 may be taken as the current flowing to it times its R. F. voltage. Neglecting harmonic components this is true because the current modulation is complete and no steady current flows. It is evident that the power output may be many times the driving power and hence oscillation can be obtained. The maximum R. F. swing of electrode 2 should be limited to about 600 volts peak. Beyond this harmonic generation increases rapidly. The maximum R. F. swing of 5 will be limited solely by the applied D. C. potential. The current values will be determined by the strength of the magnetic field. Modulation of the output may be had by varying the potential of cylinders 2 or 3 or both.

The embodiment illustrated in Fig. 4 constitutes a double ended variation of the tube of Fig. 2 which may give somewhat higher efficiency. The secondary emitter disks 1 and 1' are located in the opposite ends of the tube. Immediately

adjacent these disks are located steady potential cylinders 2 and 2' while between these cylinders is located the R. F. accelerating cylinder 3. Behind the emitter disks are located screen grids 11 and 11' respectively and behind the grids are located collector electrodes 5 and 5'. An evacuated glass envelope may or may not enclose the cylinders. A series of 4 focusing solenoids 7 are located outside the envelope coaxial therewith. A tuned radio circuit 8 is connected to cylinder 3 and another similarly tuned circuit 9 is connected to collectors 5 and 5'. A source of D. C. potential is indicated at 10.

Dimensions and potentials are made such that the circuit angle from b to b' is 180° and the circuit angles of the fast electrons from b' to a' and from b to a plus the circuit angles of the slower electrons from a to b and from a' to b' is equal to 180° . Passage of an electron having maximum bombarding potential is indicated by the dotted line in Fig. 5. It receives acceleration both at b and at b' and arrives at a' with a velocity equivalent to twice the peak R. F. voltage on 3, sustained multiplication taking place as before. Again electrons in other phase relations will arrive with lower velocities or will not arrive at all. Hence the electronic current will be completely modulated. All current beyond the value which can be maintained in focus by the magnetic field will be drawn by the electric field of 11, 11' and will pass through these grids to 5 or 5' respectively. Assuming a multiplication ratio of 6 then the current flowing to anodes 5, 5' will be five times the current flowing down the tube. Since the anodes 5, 5' may have much higher R. F. swings than does 3, the power gained may be very high.

The embodiments described above are adaptable to operation at frequencies of 600 megacycles or less. For higher frequencies it is preferred to employ confined field resonators (resonant cavities). A tube of this type embodying the invention is shown in Fig. 6. Referring to this figure a secondary emitter disk 1 is shown positioned at one end of the tube with the secondary emitter electrode 4 positioned in the opposite end and preferably in the form of a truncated cone as shown. Behind the electrode 4 is a grid 11 preferably composed of radial wires as shown in detail in Fig. 7. Behind the grid is located the collector anode 12 which is preferably in the shape of a closed cylinder as shown. An evacuated glass envelope 6 encloses these elements. A confined field resonator 13 surrounds the end of the tube adjacent the emitter disk 1 while a similar confined field resonator surrounds the collector anode 12 and a portion of the glass envelope adjacent thereto. D. C. insulation is provided at 15. Focusing solenoids 7 are employed as before. Regeneration coupling loops 16 are employed in connection with resonance cavities 13 and 14 to obtain oscillation. The load is removed by means of a coupling loop 17. A source of D. C. potential 10 is employed as before. An electric R. F. field is produced in gap 18 by resonator 13. The sum of the fast and slow transit angles from 18 to 1 and back is 180° . The same is true from 18 to 4 and back. Hence the electrons leaving 1 or 4 in the proper instant will be accelerated by the field in 18 and the secondaries produced arriving at 180° later will likewise be accelerated so that multiplication is maintained. Excess electrons are removed from 4 by the field of grid 11 and passed through 11 to collector anode 12 when 12 is at negative R. F. potential. As is the case with

the embodiment shown in Fig. 2, due to the shape of 4 and the contour of the magnetic field surrounding it, a greater density of electrons may arrive at 4 than can be held in focus when moving in the opposite direction. Hence a uni-lateral effect is obtained with a majority of electrons moving from right to left as illustrated, striking electrode 4 and a smaller number moving through the tube from left to right.

In the embodiment shown in Fig. 8 two symmetrical accelerating fields 180° apart are employed. This results in two space charge clouds moving in opposite direction. Collision of these clouds occurs in the center producing a high space charge density here so that the desired excess of electrons passes through a cylinder grid 11 to the outer cylindrical anode 12. The R. F. field of the output cavity 19 is shielded from the main beam by the cylinder grid 11.

Focusing may be accomplished as before by the use of a magnetic field but electric focusing is shown in Fig. 8. This type of focusing is obtained by the use of parabolic or concave-shaped emitter electrodes 4 and 4'. The field (equal potential lines) then follows this contour near the surface and the slow electrons coming off are directed toward the focal point. They are not greatly affected by the subsequent defocusing fields because of their high velocity. The symmetrical accelerating fields are produced by means of confined field resonators 13 and 14. These resonators produce accelerating fields at 18 and 18'. The cavities of resonators 13 and 14 are coupled to the anode cavity 19 by means of loops 20. An evacuated glass envelope 6 encloses the elements of the tube. Loop 17 is provided for removing the load. D. C. potential is supplied by source 10. Circuit angles between 18' and 4' and those between 18 and the center of the tube and between 18' and the center of the tube are indicated in the upper portion of the illustration.

Electric focusing as shown in Fig. 8 may be employed in any of the embodiments described and should be satisfactory for steady operation where space charge densities do not run high. For pulsing operation a combination of electric and magnetic focusing is probably desirable. If electric focusing were employed in the embodiment of Fig. 2 the electrodes would be made in the shapes shown in Fig. 9. If employed in the embodiment illustrated in Fig. 4 the electrodes would be as shown in Fig. 10. If employed in the embodiment illustrated in Fig. 6 the electrodes would be as shown in Fig. 9.

Since the maximum number of secondaries is produced when primary incidence is about 70° corrugations in the face of the secondary emitters illustrated above are desirable and these may take the form illustrated in Fig. 11. Fig. 12 shows on a large scale a fragment of the surface of Fig. 11 illustrating the correct angular relationship of the faces.

The invention described herein may be manufactured and used by or for the Government of the United States of America for governmental purposes without the payment of any royalties thereon or therefor.

I claim:

1. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons

which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, a confined field resonator surrounding a portion

10 of said path and having an annular gap surrounding the portion of said path lying between said coils, and means producing radio frequency oscillations in said resonator, whereby a radio frequency field is formed in and around said gap, the characteristics of said field and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°.

2. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, said coils being so located as to shield the portions of said path surrounded thereby from radio frequency fields, a confined field resonator surrounding a portion of said path and having an annular gap surrounding the portion of said path lying between said coils, and means producing radio frequency oscillations in said resonator, whereby a radio frequency field is formed in and around said gap, the characteristics of said field and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°.

3. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, said coils being so located as to shield the portions of said path surrounded thereby from radio frequency fields, a confined field resonator surrounding a portion of said path and having an annular gap surrounding the portion of said path lying between said coils, said resonator being so formed and located as to shield a portion of said path from radio frequency fields, and means producing radio frequency oscillations in said res-

onator, whereby a radio frequency field is formed in and around said gap, the characteristics of said field and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°.

4. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, a confined field resonator surrounding a portion of said path and having an annular gap surrounding the portion of said path lying between said coils, means producing radio frequency oscillations in said resonator, whereby a radio frequency field is formed in and around said gap, the characteristics of said field and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°, and means to collect a portion of the electrons travelling said path.

5. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, a first confined field resonator surrounding a portion of said path and having an annular gap surrounding the portion of said path lying between said coils, a second confined field resonator surrounding a portion of said envelope, a collector electrode enclosed in said second resonator and extending within said envelope adjacent one of said emitter electrodes, means producing synchronized radio frequency oscillations in said resonators, whereby a radio frequency field is set up along said path adjacent said gap and between said collector electrode and the one of said emitter electrodes adjacent thereto, the characteristics of said field adjacent said gap and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°, whereby secondary multiplication will be maintained in said device and a portion of the electrons travelling in said path will be collected by said collector electrode.

6. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, a pair of cylindrical coils surrounding a line passing through the centers of said emitter electrodes, said coils being longitudinally spaced along said line and coaxial therewith, means impressing a potential on said coils whereby a magnetic field is formed along said line confining the flow of electrons between said electrodes to a path coaxial with said line, a first confined field resonator surrounding a portion of said path and having an annular gap surrounding the portion of said path lying between said coils, a second confined field resonator surrounding a portion of said envelope, a collector electrode enclosed in said second resonator and extending within said envelope adjacent one of said emitter electrodes, means producing synchronized radio frequency oscillations in said resonators, whereby a radio frequency field is set up along said path adjacent said gap and between said collector electrode and the one of said emitter electrodes adjacent thereto, a grid positioned between said collector electrode and said one of said emitter electrodes means, said grid being maintained at a positive potential with respect to said one of said emitter electrodes and said collector electrode being maintained at a positive potential with respect to said grid, the characteristics of said field adjacent said gap and the dimensions of said path being such that the transit angle with respect to said radio frequency of an electron travelling said path from said field to one of said electrodes plus the transit angle from said electrode to said field of an electron emitted by impact of said first mentioned electron upon said electrode, is 180°, whereby secondary multiplication will be maintained in said device and a portion of the electrons travelling in said path will be collected by said collector electrode.

7. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, means causing electrons travelling between said electrodes to follow a prescribed path, a pair of confined field resonators surrounding portions of said path and coaxial therewith, said resonators being so located as to shield portions of said path, each of said resonators having an annular gap formed therein and surrounding said path, a third confined field resonator positioned between said first two resonators and insulated therefrom, said third resonator being coaxial with said path, and the third resonator having an annular gap formed therein, said gap surrounding said path, and being located at the center thereof, a cylindrical grid positioned in said gap, means coupling said resonators, said first mentioned gaps being symmetrically located with respect to the center of said path, the dimensions of said resonators being such that the transit angle with respect to said radio frequency of an electron travelling in said path from one of the first two of said gaps to the adjacent one of said emitter electrodes, plus the transit angle with respect to said radio frequency from said

electrodes to said field of an electron emitted by impact of said first mentioned electron on said electrode, is 180° and the transit angle of an electron travelling between said fields is 180°.

8. An electron discharge device comprising an evacuated envelope, a pair of emitter electrodes contained therein and spaced from each other, said electrodes having facing surfaces capable upon impact by electrons, of emitting secondary electrons at a ratio to said impacting electrons which is greater than unity, means causing electrons travelling between said electrodes to follow a prescribed path, a pair of confined field resonators surrounding portions of said path and coaxial therewith, said resonators being so located as to shield portions of said path, each of said resonators having an annular gap formed therein and surrounding said path, means shielding said path between said resonators, means coupling said resonators, the location of said gaps being such that the fields formed in and around each during the oscillations of said resonators will periodically accelerate the flow of electrons from the adjacent one of said emitter electrodes toward the center

of said path, the coupling between said resonators being such that said periods of acceleration of electrons travelling from each of said electrodes toward the center of said path will occur simultaneously, and means to collect a portion of said electrons at the center of said path.

9. An electron discharge device comprising an evacuated envelope, a pair of emitter electrodes contained therein and spaced from each other, said electrodes having facing surfaces capable, upon impact by electrons, of emitting secondary electrons at a ratio to said impacting electrons which is greater than unity, means causing electrons travelling between said electrodes to follow a prescribed path, means establishing a pair of synchronized radio frequency fields along said path, said fields being symmetrically located with respect to the center of said path, means shielding the remainder of said path against the occurrence of radio frequency potentials therealong and means to collect a portion of said electrons travelling said path, said collecting means being located at the center of said path.

ARTHUR A. VARELA.
